MEANS FOR FABRICATING LATH

George A. Buttress, Los Angeles, Calif., assignor
to Buttress Board Company, Los Angeles, Calif.,
a corporation of California

Application July 28, 1937, Serial No. 156,134

2 Claims. (Cl. 154—1)

This invention relates to a method and mechanism for manufacturing fabricated lath and has as its primary object the provision of a method and mechanism for producing sheet lath of the character set forth in my co-pending application for United States Letters Patent, Serial No. 137,960, filed April 20, 1937; and which lath is characterized by the embodiment of a series of hollow ribs formed of sheet fibrous material and carried on a flexible backing sheet and including a sheet metal reinforcing strip arranged interiorally of the hollow ribs and affording a support for the outer or working surfaces of the ribs.

Another object of the invention is to provide a machine of the above character which will operate to form a ribbon of paper, or similar fibrous material, with a series of parallel ribs and also to effect positioning of metallic strips within such ribs and the attachment of a backing strip to the ribbed strip in a fashion to produce a flexible ribbon of hollow lath, in an expeditious and economical manner.

Another object is to provide an effective means in a mechanism of the above character for forming the hollow ribs of dove-tail cross section.

A further object is to provide a method for forming hollow ribbed lath of sheet material to produce a corrugated flexible strip adapted to serve as a backing or lath for plaster and so formed as to afford a substantial bond for the plaster.

With the foregoing objects in view, together with such other objects and advantages as may subsequently appear, the invention is carried into effect as illustrated by way of example in the accompanying drawing, in which:

Fig. 1 is a diagrammatic view in perspective of the lath forming mechanism with the supporting frame work removed and with portions broken away; depicting the method of producing a hollow ribbed lath;

Fig. 2 is a perspective view illustrating the manner of initially forming a ribbon with corrugations preparatory to forming hollow ribs;

Fig. 3 is a view similar to Fig. 2 showing the succeeding step of coating alternate corrugations with an adhesive;

Fig. 4 is a similar view depicting the manner of applying a metal reinforcing strip interiorally of the adhesive coated corrugations;

Fig. 5 is a view illustrating a succeeding step following that shown in Fig. 4, in which an adhesive is applied to wall portions of the strip intermediate alternate corrugations;

Fig. 6 is a view showing the manner in which

the strip shown in Figs. 2, 3, 4 and 5 is worked to form the corrugations of dove-tail cross section;

Fig. 7 is a detail in section of the finished product showing the strip as illustrated in Fig. 6 applied to a backing sheet to form a sheet of hollow ribs.

Referring to the drawing more specifically A indicates generally a mechanism for forming a metal reinforced corrugated fibrous strip as shown in Fig. 6, and B designates generally a mechanism for applying a backing sheet to the corrugated strip to produce the hollow ribbed product shown in Fig. 7.

The mechanism A embodies a horizontally extending endless belt 8 passing around a pair of rollers 9 and 10 with the upper lead of the belt passing over a platform 11.

Mounted on the outer face of the belt 8 is a series of ribs 12 which extend transversely of the belt in equi-spaced relation to each other. Arranged above the roller 9 in close proximity thereto is a roller 14 formed with a series of equi-spaced parallel channels 15 which extend longitudinally of the roller and are adapted to receive the ribs 12 on the belt 8 in a fashion to effect crimping of a ribbon C of paper or similar fibrous sheet material, which is fed between the roller 14 and belt 8 from a reel D. The ribbed belt 8 and grooved roller 14 act to form the ribbon C with corrugations of rectangular cross sections including downwardly opening narrow corrugations a and upwardly opening wide corrugations b; the walls of the corrugations a conforming to the ribs 12 while the bottom walls of the corrugations b extend along the belt 8 between adjacent ribs 12.

An adhesive applicator E is provided for coating the upper surfaces of the bottom walls of the corrugations b with an adhesive c as indicated in Fig. 3, which device embodies an applicator roller 16 positioned adjacent the corrugating roller 14 and having a series of longitudinally extending ribs 17 arranged to successively enter the corrugation b and to apply an adhesive coating throughout the horizontal portions of the corrugations overlying the belt 8; adhesive being delivered from a hopper 18 between a pair of distributor rollers 19 and 20 which latter roller delivers a coating of the adhesive to the outer faces of the ribs 17 as the roller 16 revolves.

A reinforcement applicator F is provided for positioning metallic strips d onto the adhesive coated surfaces c of the corrugations b as shown in Fig. 4, which applicator embodies a magazine 21 containing a stack of the metallic strips d. The strips are in the form of channels and em-

body marginal flanges *e* and are arranged in the magazine 21 with their channel sides extending downward so that the strips *d* may be successively fed from the lower open end of the magazine 21 and positioned astride carrier ribs 22 on a roller 23 which extends transversely of the belt 8 adjacent the roller 16, and has a plurality of the ribs 22 arranged to extend into the corrugations *b* as the roller 23 revolves and the ribbon C advances. 10 A guard 24 partly encircles the roller 23 to retain the strips *d* on the carrier ribs 22 until the strips are pressed on the adhesive *c* in the corrugation *b*.

A second adhesive applicator G is provided which 15 embodies an applicator roller 25 extending transversely of the belt 8 adjacent the roller 10 in position to contact the upper surfaces of the corrugations *a* to apply a surface coat of adhesive *f* thereto as shown in Fig. 5. Adhesive is fed from 20 a hopper 26 between the roller 25 and a distributor roller 27 to effect coating of the roller 25.

The mechanism B embodies a horizontally extending endless belt 28 which passes around and is carried by a pair of hexagonal rollers 29 and 28 30; the upper lead of the belt 28 passing over a table 31. The roller 29 is disposed adjacent the roller 10 but on a plane there-above so that the corrugated ribbon C in passing from the belt 8 onto the belt 28 will lead at an upward inclination. 30

The belt 28 is fitted with a series of equi-spaced transversely extending ribs 32 of dove-tail cross section adapted to receive the corrugations *a* of the ribbon C as the latter leaves the belt 8 and 35 adhesive applicator roller 25. Extending above the belt 28 is a second endless belt 33 carried on and passing around rollers 34 and 35, the lower lead of which belt 33 passes beneath a shoe 36 and overlies the ribbed ribbon C carried by the 40 upper lead of the belt 28, and which belt 33 serves as a means for applying a flexible backing strip or sheet H from a reel J thereof onto the adhesive coated corrugations *a* of the ribbon C.

A hexagonal direction roller 37 is arranged adjacent the roller 35 over which the completed 45 fabricated strip K is passed to reel L or other suitable point of discharge.

In the operation of the invention the endless belts 8, 28 and 33, and the rollers 9, 10, 14, 16, 23 50 and 25, and the rollers 19, 20, and 27, rollers 36 and reel L are driven by conventional driving mechanism not necessary to be here shown; the parts being moved in such directions as to effect feeding of the ribbons C and strip H from their 55 respective reels D and J longitudinally through the machine.

As before stated, the ribbon C is initially formed with the rectangular corrugations *a* and *b* as shown in Fig. 2 by the roller 14 and ribbed belt 8, 60 and adhesive *c* is applied to the bottom of the corrugations *b* as shown in Fig. 3, whereupon the metal reinforcing strips are applied by the roller 23 as shown in Fig. 4 and adhered to the outer wall of the corrugation *b* by the adhesive *c*. The 65 adhesive *f* is then applied to the corrugations *a* as shown in Fig. 5 by the roller 25 and the backing strip H is applied to adhere to the corrugation *a* to form a strip of hollow ribs L.

A feature of the invention resides in upwardly advancing the corrugated strip C over the hexagonal lead of the belt 28 passing around the hexagonal roller 29 so that the rectangular corrugations *a* will be engaged by the dove-tailed strips 5 32 on the belt 28 and be caused to conform to such ribs so as to convert the corrugations *a* and *b* into dove-tailed cross section as shown in Fig. 6, in which formation the corrugations *a* and *b* are retained on applying the backing sheet H to the 10 adhesive *f* on the corrugations *a* to form the hollow ribs M, and the spaces N therebetween of dove-tail cross section as shown in Fig. 7.

It will be noted that on directing the corrugated strip C upwardly from the belt 8 around the roller 15 25, the rectangular corrugations *a* will be spread so as to permit ready entrance thereof of the corrugated ribs 32 and that thereafter on bringing the corrugated strip back to horizontal from the angular lead afforded by passing over the angular roller 29, the outer margins of the corrugations *a* will be brought closer together so as to produce the required dove-tailed cross section of the corrugations. By leading the corrugated strip C upwardly from the belt 28 the dove-tail 25 corrugations *a* are again spread to permit ready withdrawal therefrom of the corrugated rib 32. Said strip C will, however, possess sufficient resiliency to cause its corrugations *a* to resume their dove-tail shapes after said ribs 32 have been withdrawn from them, and owing to these dove-tail shapes will, by their flatwise contact with the marginal flanges *e* of the metallic strips *d*, cooperate with the adhesive material in holding said 30 metallic strips in place. 35

It will be seen from the foregoing that I have produced a method whereby a reinforced hollow strip may be readily produced in a continuous operation, the various mechanical means shown acting upon said strip simultaneously and in a 40 right to left sequence as viewed in Fig. 1 of the drawing. I claim:

1. In a machine for fabricating hollow ribbed lath, a pair of rollers, means on said rollers for forming a ribbon of fibrous material initially 45 passed between said rollers with transversely extending rectangular corrugations, a belt having exterior ribs spaced apart to successively interfit said corrugations for advancing the ribbon horizontally, means for advancing said ribbon in an upwardly arched manner to cause alternate corrugations thereof to spread at their outer margins, a belt having spaced ribs of dove-tail cross section arranged to engage the spread corrugations, and a mounting for said belt arranged to direct the corrugated ribbon horizontally after initial engagement of a rib there-with to impart a dove-tail shape to said corrugations. 50

2. The structure called for in claim 1, and 60 means for imparting a reversely arcuate movement to said ribbon to facilitate the withdrawal of said dove-tailed ribs from said corrugations after they have dove-tail shapes imparted to them. 65

GEORGE A. BUTTRESS.
